SHOULDER REST FOR A STRINGED MUSICAL INSTRUMENT

Walter James Stewart, 45 Kenilworth Gardens,
Westcliff, Southend, Essex, England

Filed Aug. 16, 1971, Ser. No. 172,355

Claims priority, application Great Britain Apr. 8, 1971

Term of patent 3½ years

Int. Cl. D17—99

U.S. Cl. D56—1

FIG. 1 is a perspective view of a shoulder rest for a stringed musical instrument showing my new design, as viewed from one side and from that face which, in use, is applied to the shoulder of the user;

FIG. 2 is a perspective view from the opposite edge and opposite face thereof; and

FIG. 3 is a side perspective view thereof.

I claim:

The ornamental design for a shoulder rest for a stringed musical instrument, substantially as shown.
